UNITED STATES PATENT OFFICE.

FRANCIS ROCKETT, OF JACKSON, MICHIGAN.

DESIGN FOR A CORSET.

SPECIFICATION forming part of Design No. 32,050, dated December 26, 1899.

Application filed November 9, 1899. Serial No. 736,429. Term of patent 7 years.

To all whom it may concern:

Be it known that I, FRANCIS ROCKETT, a citizen of the United States, residing at Jackson, in the county of Jackson and State of Michigan, have invented and produced a new and original Design for Corsets; and I do hereby declare the following to be a full, clear, and exact description of the same, reference being had to the accompanying drawing, forming a part thereof.

This invention relates to an original design for corsets; and it is embodied in the shape and configuration hereinafter described, and shown in the accompanying drawing.

In the accompanying drawing is shown but one half of a corset. The design is thus shown for convenience in illustrating, and it is to be understood that the other portion or half is in all essential respects substantially a duplicate of that shown.

The single figure of the drawing shows the corset in perspective.

A and B designate fastening-stay portions, and C the vertical intermediate stays, spaced apart.

D designates the retaining or forming bands extending across from front to rear.

The body portion E, which constitutes the essential and characteristic features of the design, is provided with a series of separated narrow transverse strips e, which are relatively closely associated, as shown. These strips bear a marked contrast with the body portion, and they are distributed substantially throughout the body, extending from front to rear.

Having thus described my invention, what I claim as new, and desire to secure by Letters Patent, is—

The design for a corset, substantially as shown and described.

In testimony whereof I affix my signature in presence of two witnesses.

FRANCIS ROCKETT.
